APPARATUS FOR CONVERTING HYDRO-CARBONS

Joseph P. Furlong, Pawtucket, R. I., assignor to
 Amarel Corporation, Newark, N. J., a corpora-
 tion of Delaware

Application February 12, 1936, Serial No. 63,475
 Renewed July 9, 1938

4 Claims. (Cl. 196—104)

This invention relates to apparatus for converting hydrocarbons by contacting the same either in liquid or vapor form directly with combustion gases.

- 5 An object of the invention is the provision of means to effect quick intimate and uniform intermixture of the hydrocarbon liquid or vapor with the combustion gases, thereby accelerating the heat absorption by the hydrocarbons.
- 10 In a preferred form of apparatus embodying the invention, there is provided a cylindrical reaction chamber having two partitions of substantial width defining a zone into which the hydrocarbon is introduced either in liquid or vapor form.
- 15 Combustion gases are provided by burning a stoichiometrical mixture of air and fuel supplied to the combustion chamber and the gases thus formed are directed through openings in said partitions of substantially less area than the 20 area of the combustion chamber. As the combustion gases enter and depart from the zone between the partitions, a great deal of turbulences is effected with the result that the combustion gases are immediately, intimately and uniformly mixed with the hydrocarbon vapors, thus facilitating the heat absorption by the hydrocarbons from the gases.

Other objects, novel features and advantages of this invention will become apparent from the 30 following specification and accompanying drawing, wherein:

Fig. 1 is a vertical section through an apparatus embodying the invention;

Fig. 2 is a section on the line 2—2 of Fig. 1, 35 and

Fig. 3 is a section on the line 3—3 of Fig. 1.

The converter comprises a tubular steel casing 10 within which is arranged a highly refractory tube 11, the right hand end of which 40 may be of smaller diameter than the remainder, this tube preferably being composed of material known commercially as alundum. The tube 11 which forms the wall of a reaction chamber C is supported centrally of the casing 10 by a cylinder 12 of heat insulating material, such for example, as heat insulating brick, although any other suitable heat insulating material may be used. The left hand end of the tube 11 and cylinder 12 abut against a plate 13 fastened to the 45 shell 10 and having a central aperture 14. Fastened to the plate 13 is a closure 15 containing an interiorly threaded boss 16. Also, a cap 17 carried by a plate 18 is connected to the closure 15 by bolts 19, the plate 18 being provided with a 50 central aperture 18a and a plurality of smaller

55 apertures 18b leading into the chamber 16a. The cap 17 is provided with an interiorly threaded boss 20 in which is arranged and exteriorly threaded pipe 21 which extends through the central aperture 18a, a slight clearance being provided between the pipe and the periphery of the aperture. A bushing 22 is threaded into the boss 16 and has its bore in axial alignment with the pipe 21. The pipe 24 leads into the chamber 17a and a pipe 25 is in communication with the 10 pipe 24. A metal tube 26 is threaded into the shell 10 and extends through the insulator 12 and refractory tube 11 near the left hand end of the shell. A spark gap 27 is mounted in the lower end of the tube 26 and a pipe 28 leads from the 15 chamber 16a to the upper end of the tube 26. A disk 29 of steel wool or the like may be arranged in the chamber 16a when gas is used as a fuel. A plate 30 provided with a discharge conduit 31 is attached by bolts to the right hand 20 end of the shell 10.

A pipe 32 for supplying hydrocarbon to the conversion chamber extends through the shell 10, cylinder 12 and tube 11. A receiving zone for the hydrocarbon is defined by two partitions 33 25 and 34 of refractory material in which are provided aligned cylindrical passages of approximately one-half the diameter of the tube 11. Around the periphery of each end of each passageway is provided a series of pockets 35 so that 30 the effective area of the two passages is greater at each end than in the middle. These pockets open toward the ends of the passageway and toward the interior thereof and are effective to create substantial turbulence in the gases passing 35 therethrough.

Fuel is supplied through the pipe 21 to the chamber 16a and air is supplied to the chamber 17a through the pipe 24 and passes through apertures 18a and 18b into the chamber 16a in 40 which the air and fuel are thoroughly and intimately admixed. If desired, steam may be introduced into the air by means of the pipe 25. The fuel mixture is then discharged through the bushing 22 into the combustion chamber through 45 the aperture 14. The tube 28 by-passes a small stream of the combustible mixture from the chamber 16a and this stream is ignited at the spark gap 27 with resultant ignition therein of the fuel mixture passing through the orifice 14 50 into the chamber C. The hydrocarbon to be converted is introduced through the pipe 32 either in the form of liquid or vapor and is discharged into the receiving zone between the partitions 33 and 34 where it mixes with the combustion gases 55

entering this zone through the opening in partition 33. The mixed combustion gases and hydrocarbon vapors flow through the passage in the partition 34 into the chamber C. The turbulence given the combustion gases by passage through the partition 33 and the turbulence given the mixture of gases and vapors by passage through the partition 34 immediately effect intimate and uniform admixture of the gases and vapors so that the heat absorption by the hydrocarbon vapors is at a maximum. This condition promotes the desired reactions and facilitates the conversion of the hydrocarbons. After the desired conversion has been effected, the combined gases and vapors are discharged through the pipe 31 and if desired are cooled by vapors or liquid introduced through the pipe 36.

The temperatures to be maintained in the chamber C depend upon the reactions desired. The amount of steam added to the combustible mixture is dependent upon the hydrocarbon which is to be converted and is limited to the amount required to prevent deposition of free carbon in the tube 11. The combustion of both the fuel and oxygen in the combustible mixture is complete by reason of the stoichiometrical proportions and thorough mixing so that there is no free oxygen in the combustion gases and there is, therefore, no possibility of high temperature reactions involving free oxygen in the reaction. The temperature at which the combustion gases contact with the hydrocarbon is substantially the flame temperature of the combustible mixture inasmuch as no quenching of the gases is effected before contact. The heat absorption by the hydrocarbons is maximum by reason of the high temperature of contact and the immediate intimate and uniform admixture of the combustion gases with the hydrocarbons.

While the invention has been described as embodied in apparatus provided merely with a pair of partitions forming a single zone, it is to be understood that the invention contemplates as well an apparatus equipped with several partitions defining a plurality of receiving zones to any one of which or to all of which hydrocarbons may be supplied as described.

The combustion gases are introduced into the receiving zone without substantial temperature change and the maximum temperature attained by the mixture of hydrocarbons and combustion gases is of the order of 2500° F. depending upon the type of hydrocarbons and the ratio of hydrocarbons to combustion gases. Throughout the mixture of combustion gases and hydrocarbons in the reaction zone, there is a very decided temperature gradient. As typical of this temperature

gradient, the temperature registered by a thermocouple T₁ in one run was approximately 1400° F. while the temperature registered by a thermocouple T₂ was approximately 1000° F. However, this temperature difference is not the full measure of the temperature gradient since both thermocouples are spaced from the ends of the reaction zone.

I claim:

1. A device of the character described comprising an elongated chamber, means for introducing combustible mixture into said chamber at one end thereof, an outlet at the other end of said chamber, a pair of partitions in said chamber defining a receiving zone of the same cross-section as said chamber, and means for introducing hydrocarbons into said receiving zone, each partition having a single passageway of substantially less cross-section than said zone and of greater length in the direction of flow through said chamber than the distance between said partitions. 10 15 20

2. A device of the character described comprising an elongated chamber, means for introducing combustible mixture into said chamber at one end thereof, an outlet at the other end of said chamber, a pair of partitions in said chamber defining a receiving zone, and means for introducing hydrocarbons into said receiving zone, said partitions having cylindrical passages 25 30 35 leading to and from said zone and being of larger effective diameter at their ends than intermediate the same.

3. A device of the character described comprising an elongated chamber, means for introducing combustible mixture into said chamber at one end thereof, an outlet at the other end of said chamber, a pair of partitions in said chamber defining a receiving zone, and means for introducing hydrocarbons into said receiving zone, said partitions having cylindrical passages leading to 40 45 50 and from said zone and having a series of peripheral pockets opening endwise and inwardly to effect variation in the effective area of said passageways throughout their length. 35

4. A device of the character described comprising an elongated chamber, means for introducing combustible mixture into said chamber at one end thereof, an outlet at the other end of said chamber, a pair of partitions in said chamber defining a receiving zone, and means for introducing hydrocarbons into said receiving zone, said partitions having cylindrical passages leading to and from said zone and having a series of short peripheral channels extending inwardly 55 from each face of the partitions. 50 55

JOSEPH P. FURLONG.
